POWER OPERATED CAN OPENER WITH VARIABLE AUTOMATIC SHUT-OFF

Robert J. Scott, Blue Springs, William A. Chappell and Joseph L. Grant, Raytown, and William J. Landry, Blue Springs, Mo., assignors to John C. Hockery, Kansas City, Mo., trustee for Henry J. Talge and Foster L. Talge

Filed Feb. 15, 1960, Ser. No. 8,699
10 Claims. (Cl. 30—4)

This invention relates generally to electrically powered can openers and refers more particularly to improvements therein with respect to providing a variable shut-off operable to positively and automatically control the length of the cutting operation so as to adapt the can opener to timed operation with various sizes of cans.

One of the objects of the present invention is to provide improvements in electrically powered can openers of the lever type generally disclosed in the Aberer et al. Patent 2,902,757, issued September 8, 1959, which improvements are directed to the incorporation in such a can opener of means for relating the period of operation of the motor to the size of the can being opened. It is a special feature of the present invention that the automatic control of the operational period is achieved while still retaining all of the advantages of the manual power control resulting from the arrangement described in the aforementioned patent.

Another object of the present invention is to provide an automatic variable shut-off for power operated can openers of the character described in which, through the unique relationship of the functioning parts, the electrical system is of extreme simplicity, requiring but a single switch.

A further object of the invention is to provide a variable selective control mechanism for power operated can openers which is so arranged that the control can be overridden by the operator to increase the period of cutting if such proves necessary or desirable.

Still another object of the invention is to provide a power operated can opener with a variable automatic shut-off which is capable of adjustment to the selected period of operation with ease and facility, and without interfering with or requiring adjustment of the functional can cutting and feeding elements of the unit.

A further object of the invention is to provide a simple and reliable mechanism for accomplishing the foregoing results. The variable shut-off elements and operating mechanism are so arranged that they can be incorporated into certain presently known can openers without requiring any basic redesign or retooling.

Still another object of the invention is to provide a variable shut-off control for power operated can openers of the type described in which the can opener is capable of manual control in the event of failure or malfunction of the automatic control mechanism.

Other and further objects of the invention together with the features of novelty appurtenant thereto will appear in the course of the following description.

In the accompanying drawings which are to be read in conjunction with the specification and in which like reference numerals indicate like parts in the various views:

FIG. 1 is a front elevation of a typical power operated can opener embodying the features of the invention;

FIG. 2 is a rear elevation of the can opener, slightly enlarged, with the casing removed and with parts of the drive worm and gear broken away for purposes of illustration;

FIG. 3 is a top plan view of the can opener, the outer

2

casing being again absent and part of the base being broken away;

FIG. 4 is a fragmentary sectional view taken generally along the line 4—4 of FIG. 3 in the direction of the arrows;

FIG. 5 is a fragmentary front elevation illustrating the relationship between the hand lever and cutter wheel plate and between the latter and the feed wheel, at the moment of firm engagement of the cutter wheel with the can lid at the inception of the operating cycle;

FIG. 6 is a fragmentary rear view showing the relationship between the thrust element and shut-off control arm when the hand lever is in the position illustrated in FIG. 5;

FIG. 7 is a fragmentary sectional view taken along the line 7—7 of FIG. 6 in the direction of the arrows;

FIG. 8 is a view similar to FIG. 5, but illustrating the relationship of the hand lever, cutter wheel plate and feed wheel following initial displacement of the plate and shifting of the shut-off control arm to motor starting position;

FIG. 9 is a sectional view similar to FIG. 7 illustrating the relationship of the thrust element and shut-off control arm when the opener is in the condition illustrated in FIG. 8;

FIG. 10 is a view similar to FIGS. 5 and 8, but illustrating the plate in its fully depressed condition and just prior to piercing of the can lid;

FIG. 11 is a view similar to FIGS. 7 and 9, but illustrating the position and relationship of the thrust element and shut-off control arm when the can opener is in the condition illustrated in FIG. 10; and

FIG. 12 is a fragmentary detail taken generally along the line 12—12 of FIG. 3 in the direction of the arrows.

Referring now to the drawings, the invention will be described in connection with an electrically powered can opener having the construction disclosed in the aforementioned Patent 2,902,757. All of the details of the basic can opener structure and operating mechanism are described in full in that patent and will not be repeated here except as necessary to clarify the relationship with the improvements herein set forth.

Generally speaking, the can opener unit includes a base 10 from the forward edge of which rises an essentially vertical face plate and support structure 11 which serves the purpose of supporting at its upper end the operating mechanism of the can opener. A hollow, generally three-sided casing 12 houses the various operating parts of the drive and control mechanism. For reasons of simplicity in description this housing has been shown only in FIGS. 1, 5, 8 and 10, being absent from the remaining figures.

As may be determined in greater detail from the fore-mentioned patent, the basic operating mechanism of the can opener unit includes a rotary feed wheel 13 with which cooperates a cutter wheel 14. The feed wheel is secured to a drive shaft 15 which is supported for rotation about a fixed axis extending horizontally from the face plate 11, being journaled with respect to the latter in a boss 11a which projects from the rear side of the face plate (see FIG. 3). While the feed wheel is mounted for rotation about a fixed axis, the cutter wheel is carried by a plate structure 16 which is operable in response to manipulation of a hand lever 17 to separate the cutter wheel from the feed wheel to permit insertion of a can rim therebetween, and to again bring the two together so as to pierce the can lid. The position of the hand lever 17 and plate structure illustrated in the solid lines in FIG. 1 is that which obtains after the lid has been pierced. The broken line position illustrates the positions of the hand lever, plate and cutter wheel prior to instituting operation.

As again may be seen from the Aberer et al. patent, the movement of the plate 16 between the solid and broken lines positions is in response to the swinging of the hand lever 17 between its solid and broken line positions. The plate is coupled with the hand lever through an eccentric cam arrangement, one element of which is seen at 18. The cam is keyed to the hand lever 17 and acts as a crank arm for moving the main body of the plate about the feed wheel axis between the two positions shown.

The left-hand end of the plate 16 moves generally linearly in a horizontal direction toward and away from the feed wheel axis in response to manipulation of the hand lever between the positions shown. This is due to the fact that the plate 16 is provided with a rearwardly extending arm 19 which extends through a large aperture A in the face plate 11. (See FIGS. 6 and 7.) The aperture A is provided with a horizontal upper edge 11b and lower edge 11c. Normally the upper surface of arm 19 is maintained in sliding engagement with edge 11b by a tension spring 20 which is connected at one end with a second lug 16a extending rearwardly from plate 16 through the aperture A, and at the other end with a fixed lug 21 extending rearwardly from the face plate 11 above the aperture. The action of the cam coupling between hand lever 17 and plate 16 causes the arm 19 to slide horizontally along edge 11b, the maximum displacement to the right (as viewed in FIG. 2) occurring with the hand lever in a position midway between the solid and broken line positions of FIG. 1. The midway position is illustrated in FIGS. 5 and 6.

As also disclosed in the aforementioned patent, plate structure 16 and hand lever 17, when in the solid line positions, are coupled to operate as a unit capable of limited rotary displacement in a clockwise direction (FIG. 2) about the axis of the feed wheel. In other words, by pressing downwardly on the hand lever 17, both the hand lever and plate 16 are caused to rotate about the shaft 15 a limited distance. Rotation of the plate relative the shaft when the hand lever is separated from the plate can also be occasioned, this being accomplished by inserting a can lid between the cutter wheel and feed wheel and applying pressure to the hand lever, as is shown in FIGS. 5, 8 and 10, the can lid serving to transmit the thrust applied to the handle and transform it into a moment tending to turn the plate about the shaft 15. More will be said of this later. The left-hand end of plate structure 16 is, of course, biased toward and normally maintained in the position illustrated in solid lines in FIG. 1 by the tension spring 20, as previously described. The aperture A is large enough to accommodate the necessary movement of the lug 16a, and thus plate structure 16, about the shaft 15 upon depression of the hand lever.

The driving power for the can opener is supplied through the medium of electric motor 22. The motor is vertically oriented on the base 10 and terminates in a drive shaft 23 provided with a worm 23a. The worm drivingly engages the teeth of a gear 24 secured to the horizontal feed wheel shaft 15. Preferably, the gear 24 is constructed of nylon or other tough plastic. It is secured to shaft 15 by means of a flanged collar 25 press fitted onto the end of the shaft, one face of the gear body being secured to the collar by screws 26.

The electrical control for the motor comprises a snap acting switch S which is mounted by suitable supporting structure on an insulating base 27 to the rear of the face plate 11 and below the aperture A. As best seen in FIG. 12, switch S includes the fixed contact 28 and the normally open but movable contact 29. The switch may be of the conventional over-center type illustrated, having the operating arm 30 terminating in the depressor portion 30a at its free end. As will be evident, the portion 30a is positioned in the downward path of the lug 16a so that the contacts will be closed when the latter lug is displaced downwardly by limited movement of the plate 16 from

its normal position against the force of the spring 20. It will be understood that the switch S is interposed in series in the motor electrical circuit, the leads 31a and 31b being connected with the respective contacts 28 and 29.

5 The switch operating arm 30 is continually biased upwardly so that when downward pressure is removed from the portion 30a the arm will return to its original position and cause contact 29 to disengage from the fixed contact and cause the motor to stop. The arm is so arranged with the movable contact that the initial increment of downward movement of the arm causes closing of the contacts. By the same token, reopening of the contacts does not occur until the arm is near the upper end of its movement.

15 It may help in obtaining a clear understanding of the invention to repeat that with the exception of the specific arm 19 herein shown, all of the features of the can opener described thus far are disclosed in the Aberer et al. patent referred to above, and that such details of construction 20 as are not herein specifically set forth can be gained from that patent. Thus far we have set forth a manually controlled power operated can opener in which the operation of the motor is made responsive solely to the application and release of external pressure to the hand lever 25 by an individual, the period of operation depending on how long the pressure is kept on the hand lever. The present invention is designed to supplement this arrangement with novel means for automatically maintaining the motor energized following starting, even though manual 30 pressure is removed from the hand lever 17, and to stop the motor after a predetermined interval has passed, without changing the basic nature of the can opener mechanism.

35 One of the principal elements of our present invention comprises a pivotal switch control member 32 which in the illustrated embodiment is in the form of an elongate arm pivoted at one end by a screw 33 for movement about an axis parallel with the feed wheel shaft 15. The member 32 is mounted behind the face plate 11, the pivot screw 33 being received and retained in a boss 44 extending rearwardly from and secured to the face plate. As viewed from above (FIG. 3) the control member is provided with a rearwardly bent portion 32a which continues in an extension 32b disposed fairly close to the plane of the forward face of the gear 24. A reverse bend 45 32c is provided at the outer end of extension 32b and continues into a further extension 32d from which the arm turns downwardly to provide the vertical leg 32e which terminates in a horizontal shoe portion 32f, more of which will be said later.

50 It will be observed that secured to the intermediate portion 32b of the control member is a leaf spring 34 which terminates in a free end disposed closely adjacent the forward face of gear 24. The end of spring 34 is equipped with a stylus 35 which is resiliently pressed by the spring into contact with the face of the gear.

55 As may best be seen in FIG. 4, the forward face of the gear 24 is provided with a groove 24a spiraling outwardly about the gear axis. The inner end of the spiral groove terminates at the outer margin of a circular face portion 24b in which the stylus is free to ride without causing any displacement of the control member 32. So long as the stylus remains in the position shown in FIG. 4, the groove will have no influence on the control arm. 60 However, if the arm 32 is pivoted downwardly (for example to the broken line position of FIG. 2) the stylus will be moved downwardly and transversely across the groove and come to rest in the groove at a point determined by the extent of pivotal displacement of the control member. The resilient character of the leaf spring 34 permits the stylus to ride in and out of the groove valleys as it moves transversely across the face of the gear. The orientation of the groove 24a in the gear is such that 65 when the motor is started the surfaces of the groove will

progressively drive the stylus back toward the gear center, the stylus carrying with it the control member 32.

The normal position for the control member 32 is that illustrated in the solid lines of FIG. 2. This corresponds to the position of the stylus illustrated in solid lines in FIG. 4. No matter to what extent the control member may have been displaced during any phase of the operation, it always returns to this normal position in response to rotation of the gear 24, which is always in the same direction.

The downward displacement of the control member during operation is accomplished under the influence of a thrust member 36 which is connected with and depends from the outer end of arm 19. Referring to FIGS. 2 and 7, it will be observed that the thrust member 36 is pivotally connected with the end of a headed pin 37. The pin extends through a suitable aperture in the arm and is retained against removal by a nut 38 which is connected with the threaded end of the pin. Surrounding the pin between its head and arm 19 are the coils 39 of a torsion spring having one end 39a in bearing engagement with the thrust member, and the other end 39b retained by the arm 19. Obviously, spring 39 exerts a moment upon thrust member 36 tending to maintain it in yielding sidewise engagement with the control member 32. The thrust member is provided with a rounded shoulder 36a which is normally disposed above and which is operable to engage, under certain conditions of operation, the upper surface of portion 32g of the control member, thereby to apply downward thrust upon the control member responsive to downward movement of the arm 19. However, it will be noted that if downward movement of the control member is restricted or interfered with, the shoulder 36a can ride outwardly until it clears the edge of surface 32g of the control member, thus permitting the arm 19 to move downwardly independently of the control member.

The control member 32 is provided with a notch or recess 32h in its upper surface which is so located and has such a depth that when the plate structure 16 is in its normal can cutting position vis-a-vis the hand lever 17 (the solid line position of FIG. 1) the shoulder 36a of the thrust member is capable of moving up and down in response to movement of the plate structure without contacting the control member. The shoulder 36a only engages the portion 32g of the control member when the plate is in a position corresponding to a position of the hand lever midway between the solid line and broken line positions of FIG. 1.

As may best be seen in FIGS. 3 and 12, control member 32 is provided with a laterally extending tongue 40 which overlies and is capable of depressing the depressor 30a of the switch operating member 30 upon downward pivoting of the control member. In the normal position of the control member the tongue 40 is just above the depressor, leaving the contacts of the switch open. Initial downward movement of the tongue 40 results in closing of the contacts through the medium of the switch operating member 30.

The extent of permissible movement of the control member 32 downwardly from its normal position is governed by a cam body 41 which is positioned near the base of the unit and in the path of the shoe portion 32f of the control member. The cam surface 41a is contoured substantially as shown. The cam body 41 is rotatable, being secured to a shaft 42 which is journaled in a bearing boss 43 which may conveniently be cast as an integral part of the face plate 11. A friction imposing take-up spring 45 is interposed between a retainer flange 42a and the confronting end of the boss 43. The shaft 42 extends through the face plate and has secured to its outside end a control knob 46 fitted with an indexing pointer 46a. The pointer cooperates with a scale 47 marked off in increments of average can diameters and also including an area marked "manual."

The configuration of the cam surface 41a in the illustrated embodiment is such that it provides for progressive limitation of the downward displacement of the control member as the cam body is turned clockwise on its shaft 42 as viewed in FIG. 2. Thus the solid line position of the cam shown in FIG. 2 corresponds to the maximum permissible downward displacement of the control member; the intermediate position (in broken lines) at 41' represents essentially a permissible motion of approximately one-half the full range; and the position 41" (also in broken lines) represents a position for the cam which prevents any downward movement of the control arm. To assist in understanding the relationship between the index or scale on the exterior of the face plate with the cam position, the pointer 46a is shown in FIG. 1 in the corresponding broken line positions it assumes, these being identified as 46a' and 46a" respectively. It will be observed that in the illustrated embodiment the range of rotation of the cam 41 is through an arc of 180°, the lowermost position being indexed by an extension 41b on the cam body engaging an abutment 11d on the rear of the face plate and the uppermost by the engagement of the cam surface 41a with such abutment.

The operation of the invention will perhaps be best understood by explaining it in connection with the opening of a large diameter can.

In this case, the first action taken is to manipulate knob 46 to index the pointer in the "large" area of the scale 47 which results in the cam position illustrated in solid lines in FIG. 2, as earlier explained. The hand lever 17 is then swung upwardly and outwardly to the broken line position of FIG. 1, which, as previously noted, separates the cutter wheel 14 from the feed wheel 13 and permits insertion therebetween of the rim and adjacent lid portion of a can. While holding the can in this position the hand lever is moved back toward its original position until the lid is engaged firmly between the cutter wheel and feed wheel. This is the condition of the assembly illustrated in FIGS. 5, 6 and 7. In these and succeeding figures the can body is identified by reference numeral 50 and the lid by 51.

Due to the previously described eccentric coupling between the hand lever 17 and plate structure 16, the plate structure 16 is, in the FIG. 5 condition, so located that the shoulder 36a of thrust member 36 now overlies the upper surface 32g of the control member 32. In other words, the plate structure has shifted slightly to the right of its FIG. 2 position. The relationship now existing between the thrust member and control member is clearly shown in FIGS. 6 and 7.

To produce piercing of the can lid and start the operation of the motor additional counter-clockwise pressure is applied to the hand lever, sufficient pressure being applied to overcome the resistance of the plate spring 20 so that the plate structure is pivoted along with the hand lever, causing the arm 19 to disengage from edge 11b and pushing the thrust member 36 downwardly. The tension in spring 20 is ordinarily insufficient to hold the plate structure against the turning moment imposed thereon by the engagement of the cutter wheel 14 with the can lid.

The downward movement of the thrust member 36 is accompanied by downward pivoting of the control member 32 because of the engagement of the shoulder 36a therewith, and the control member will be moved downwardly until it is stopped by engagement of the shoe 32f with the cam surface 41a of cam body 41. The motion of the control member results in downward displacement of the stylus 35 across the spiral groove 24a and the setting of the stylus in a position (35" in FIG. 4) near the rim of the gear. At the same time the switch lug 16a on the plate structure engages and depresses the switch operating arm 30 to close contacts 28 and 29 and start the motor.

As the motor starts the operator continues to hold the

closing or piercing pressure on the hand lever 17 and the combination of the rotation of the feed wheel and hand applied pressure causes the cutter wheel to pierce the can lid. As the cutter wheel moves through the lid, the hand lever approaches and comes into its aligned or closed position relative to the plate structure. Ordinarily the tension spring 20 will, once the lid is pierced, serve to again raise the end of the plate structure 16 back to the FIG. 7 position. In other words, once piercing of the can has taken place and the hand lever has reached the solid line position of FIG. 1, the pressure on the hand lever can be removed and, as will be seen, the unit will operate automatically from this point on.

The release of the hand lever, and return of the plate structure 16 to its upper position as limited by arm 19, removes from the switch arm 30 the depressing pressure of lug 16a. However, the tongue 40 on the control member 32 now takes over, holding the switch closed until the control member again returns to its normal position. It is thus obvious that so long as the control member 32 remains below its normal position, the motor will continue to run and cause the feed wheel 13 to feed the can into the cutter wheel 14.

The spiral groove 24a in the face of gear 24 serves the function of returning the control member 32 to the normal position in timed relation with the number of revolutions of the feed wheel succeeding the initiation of operation of the motor. As the gear rotates, the stylus 35 is displaced back toward the center of the gear, lifting along with it the control member to which it is attached. During this time the tongue 40 continues to hold switch S closed and the motor continues to operate. Just as the control member 32 reaches its normal position, the contact 29 of the switch snaps open and the motor stops without requiring any action by the operator.

It will be evident that the time interval of operation of the motor can be varied by simply changing the amount of downward displacement permitted the control member 32. This function is, as previously noted, served by cam body 41 which can be positioned to limit the travel of the control member to any desired degree. The shorter the travel, the shorter the time interval of operation of the motor and the smaller the can that will be completely opened.

It may develop in certain cans that piercing of the lid will not take place until the plate structure 16 has reached a position where arm 19 engages the lower edge 11c of aperture A (FIGS. 10 and 11) and is immobilized against further turning with the hand lever. Since the control member 32 is intercepted by cam 41 before this occurs, the thrust member 36 merely rides outwardly on and is disengaged from its thrust connection with the control member so that the plate structure can continue to move independently of the control member. When the plate structure again lifts, the torsion spring 39 causes the shoulder 36a to reassume its position above surface 32g of the control member. It will be understood that the strength of the torsion spring is sufficient to hold the shoulder 36a inwardly on surface 32g so long as the only resistance encountered in movement of the control member is that imposed by the resistance to movement of the stylus in and out of the groove valleys.

By turning the cam body 41 to prevent movement of the control member 32 from its normal position (see 41" in FIG. 2) the unit becomes subject to manual control only. The thrust member 36 moves without causing any displacement of control member 32 and the only control over the switch is that provided by the plate lug 16a.

It will further be evident that should it at any time be desired to override the automatic shut-off herein provided, this is accomplished simply by pressing downwardly on the hand lever 17, causing plate structure 16 to turn therewith and to depress the switch operating arm 30 by the lug 16a.

From the foregoing it will be seen that this invention

is one well adapted to attain all of the ends and objects hereinabove set forth together with other advantages which are obvious and which are inherent to the structure.

5 It will be understood that certain features and sub-combinations are of utility and may be employed without reference to other features and subcombinations. This is contemplated by and is within the scope of the claims.

10 As many possible embodiments may be made of the invention without departing from the scope thereof, it is to be understood that all matter herein set forth or shown in the accompanying drawings is to be interpreted as illustrative and not in a limiting sense.

Having thus described our invention, we claim:

1. In a power operated can opener, the combination of a rotatable feed wheel, an electric motor drivingly connected with said feed wheel, switch means connected with said motor and having a motor energizing condition and a motor deenergizing condition, a cutter member, a carrier for said cutter member, said carrier supported for movement of the cutter member relative to the feed wheel into and out of can cutting relationship with the feed wheel, a movable switch control member operably connected with said switch means whereby said control member has a first position relative to said switch means wherein the switch means is in the motor deenergizing condition and a second position wherein the switch means is held thereby in the motor energizing condition, thrust means connected with said carrier and cooperating with said control member whereby to shift said control member to said second position in response to movement of said carrier and can cutter member into said can cutting relationship, and spiral camming means connected with and driven by said motor and having engagement with said control member, said camming means causing said control member to return to said first position in response to a preselected number of revolutions of said feed wheel whereby to cause said motor to stop upon the completion of said preselected number of revolutions.

40 2. In a power operated can opener, the combination of a rotatable feed wheel, an electric motor drivingly connected with said feed wheel, switch means connected with said motor for starting and stopping same, said switch means including a switch operating member resiliently biased toward and normally disposed in the stop condition, manually depressible means for engaging said operating member to displace same and start said motor, a body coupled with said feed wheel for rotation therewith, said body having a spiral camming groove disposed in a plane substantially normal to the axis of rotation of said body and the groove spiraling about the axis of rotation, a movable control member having a stylus biased toward said groove, said control member displaceable in a path to place said stylus at varying distances from one end of the groove, the groove operating to return said stylus and control member toward one end of the groove upon rotation of the feed wheel, thrust means actuated responsive to depression of said manually operable means and operable to engage and displace said control member in a direction away from said one end of said groove, and means connected with said control member and operable to engage and prevent return of said switch operating member to its normal position until the stylus has moved a selected distance back toward said one end of said groove in response to rotation of said body.

55 3. The combination as in claim 2 including adjustable stop means positioned in the path of said control member and operable to control the extent of displacement of said control member responsive to depression of said manually operable means.

60 4. The combination as in claim 3 wherein said thrust means includes mechanism operable to permit disengagement of said thrust means from said control member and further depression of said manually operable means in the event said control member is immobilized.

5. The combination as in claim 3 wherein said stop means comprises a rotatably adjustable cam body having an eccentric cam surface whose position relative the control member is changed responsive to rotation of the cam body.

6. The combination as in claim 5 including means for visually indexing the cam body in a selected position.

7. In a power operated can opener of the type having an electric motor, a rotary feed wheel coupled with said motor and driven thereby, a cutter wheel, a shiftable carrier for said cutter wheel supported for movement of the cutter wheel toward and away from the feed wheel whereby to permit insertion of a can top therebetween, means for shifting said carrier, and further means mounting said carrier for limited movement in response to can piercing pressure when applied to said last named means and prior to piercing of said can, the combination therewith of electrical switch means connected with said motor for starting and stopping same, said switch means including a switch operating member resiliently biased toward the stopped condition, a movable switch control member associated with said carrier member and having a normal position out of engagement with said operating member, said control member movable in a path to engage said operating member and cause same to start said motor in response to said limited movement of said carrier, and means driven by

5 said motor and operatively associated with said control member to return same to said normal position in response to a preselected number of revolutions of said feed wheel whereby to disengage from said operating member and cause said motor to stop.

10 8. In a power operated can opener as in claim 7, the combination wherein means are provided for variably controlling the displacement of said control member, said last named means comprising an adjustable stop disposed in the path of said control member.

15 9. In a power operated can opener as in claim 7, the combination wherein said last named means includes a spiral camming surface connected with said feed wheel and rotatable therewith.

20 10. In a power operated can opener as in claim 7, the combination which includes means on said carrier member operable to engage said switch operating member independently of movement of said control member upon said limited movement of said carrier member in one direction.
